BOTTLE

Bernard A. Berns, Chicago, Ill., assignor to Dad's Root Beer Company, a corporation of Illinois

Filed Nov. 17, 1960, Ser. No. 62,871

Term of patent 14 years

(Cl. D58—8)

Fig. 1

Fig. 2

FIGURE 1 is a side elevational view of a bottle showing my new design, and

FIG. 2 is a top plan view thereof.

The band-like portions are continuous around the bottle and are plain and unornamented on the side not shown.

The characteristic features of my design reside in the combination on the bottle disclosed of the keg representation about the periphery below the plain neck portion in further combination with the label receiving surface of the configuration shown.

I claim:

The ornamental design for a bottle, substantially as shown and described.
